UNITED STATES PATENT OFFICE

123,508

DESIGN FOR A GAME BOARD

Andy H. Moore, Flint, Mich.

Application July 31, 1940, Serial No. 94,071

Term of patent 7 years

To all whom it may concern:

Be it known that I, Andy H. Moore, a citizen of the United States and a resident of Flint, in the county of Genesee and State of Michigan, have invented the new, original, and ornamental Design for a Game Board, of which the following is a specification.

Reference is had to the accompanying drawing forming part thereof, in which:

Figure 2 is a perspective view of the other side of the same game board.

I claim:

The ornamental design for a game board, as shown.

ANDY H. MOORE.
